FIGURE 1 is a plan view of an electric knife handle or similar article embodying my design;

FIGURE 2 is a side view thereof, the other side being similar in appearance;

FIGURE 3 is a bottom view thereof;

FIGURE 4 is a front end view thereof; and

FIGURE 5 is a rear end view thereof.

The design is characterized by the long side ribs having angularly disposed walls extending along the sides of a raised center rib of rectangular plan view extending almost from end to end of the handle, the side ribs being pronounced at the forward portion of the handle and gradually being less pronounced as the side ribs sweep rearwardly and slightly upwardly, all as shown in the drawing.

A knife blade is shown in broken lines for purposes of illustration.
